CLAIM

The ornamental design for a paving stone, as shown and described.

DESCRIPTION

FIG. 1 is a top and side perspective view of a paving stone showing one embodiment of my new design;

FIG. 2 is a top and side perspective view of a paving stone showing another embodiment thereof; and,

FIG. 3 is a top and side perspective view of a paving stone showing a further embodiment thereof.

The surfaces or portions of the article not shown in the drawing or described in the specification form no part of the claimed design.
